UNITED STATES PATENT OFFICE

2,285,631

ACOUSTICAL TILE

Leon F. Urbain, Chicago, Ill.

Application July 27, 1939, Serial No. 286,883

8 Claims. (Cl. 72—118)

The present invention relates to an improved method and means for securing or mounting wall or ceiling units upon an adjacent supporting structure.

Yet more particularly, the present invention contemplates the provision of a clip or fastening element suitable for permanently and expeditiously securing panels or sections to a subjacent supporting structure, which clip or fastening element is concealed in the finished structure so as to provide a wall surface uninterrupted by visible fastening means.

The present invention relates to a tile clip of the general type and character disclosed and claimed in my United States Patent No. 2,129,975, granted September 13, 1938, and having a portion adapted to be supported by a subjacent supporting structure. This portion is integral with a web carrying opposed prongs for engaging within the edges of the acoustical tile members at points spaced substantially from the corners thereof. While my prior patent contemplates the securing of the clip to the underlying structure in any suitable manner, it specifically illustrates the interengagement of the clip with a supporting channel member.

The present invention relates to a tile clip particularly adapted for securement to conventional furring strips and contemplates the construction of a clip adapted for interengagement with such supporting strips to provide a rigid, permanent construction wherein all possibility of sagging is eliminated and the tiles are held in a uniformly predetermined plane. Furring strips are conventionally formed of wood or some similar material, affording a base to which the fastening members or clips are nailed. It has been discovered that the fastening or nailing, in accordance with conventional procedure, may and frequently does result in loosening of the fasteners and sagging of the parts supported thereby, while at the same time the forces applied in nailing may tend to disarrange the tiles from their proper relationship and result in an irregular structure.

It is, accordingly, an object of the present invention to provide a tile clip construction as above, adapted for nailing to a furring strip wherein the tile supporting forces are substantially resolved to act transversely of the body of the fastener, whereby the influences tending to loosen the interengagement of parts are eliminated.

An additional object of the present invention is to provide a clip construction such as the fore-

going providing a recess or corner-engaging portion for embracing a corner of a furring strip against sagging or relative twisting. That is to say, the present clip is provided with portions coacting with angularly disposed surfaces of the furring strip adjacent the corner so that relative rotation or movement of the clip with respect to the axis of the strip is resisted and the tile engaging portions restrained from varying in position with respect to the supporting wall.

In co-operation with the immediately foregoing object, the present invention additionally contemplates the provision of a relatively wide web portion extending from the corner-engaging means for supporting the tile in such a manner that the supporting forces are resolved in the plane of the web whereby to inhibit the creation of bends or strains therein.

Other and further objects will be apparent from the following description when taken in connection with the accompanying drawings, wherein:

Figure 1 is a perspective view of a portion of a ceiling assembled in accordance with the present invention;

Figure 2 is a detailed perspective view showing the manner in which the present clip members interengage and support the edge of an acoustical tile;

Figure 3 is an elevational view showing a partially constructed portion of an upstanding wall assembled in accordance with the present invention;

Figure 4 is a perspective view of a pair of proposed clips forming a preferred embodiment of the present invention;

Figure 5 is a detailed sectional view taken on the line 5—5 of Figure 1;

Figure 6 is a perspective view of a portion of a ceiling employing alternative clips embodying the principles of the present invention, but wherein the acoustical tiles are arranged in so-called "square or matched joints" as opposed to the so-called "staggered joints" disclosed in the previous embodiment;

Figure 7 is a detailed perspective view of an end portion of the ceiling construction shown in Figure 6 for illustrating the manner in which the clip of Figure 6 coacts with the furring strip and tile units;

Figure 8 is a detailed sectional view taken on the line 3—3 in Figure 7;

Figure 9 is an elevational view of a portion of wall constructed similar to the ceiling structure of Figure 6; and

Figure 10 is a perspective view of the tile clip construction employed in the structures illustrated in Figures 6 to 9.

Referring to the drawings in detail, wherein several illustrative embodiments of the present invention are shown, Figure 1 illustrates a ceiling construction comprising a subjacent supporting ceiling or partition 10 having furring strips 12 to which are secured acoustical tiles 14. The furring strips 12 in the present embodiment are capable of receiving nails or other fasteners and in turn are secured to the wall 10 in any conventional manner.

The so-called acoustical tiles 14 comprise in the illustrative embodiment rectangular slabs or sheets of a wall-surfacing material which, in the present instance, comprises a relatively soft yielding material normally formed of compacted and bonded fibers laid edge to edge to form a continuous ceiling or surface.

The present invention contemplates the permanent and expeditious securing of the tiles to the furring strips by fastening means which are concealed, thus obviating the unsightly appearance of conventional fasteners and the marks resulting from their application. The present fasteners comprise clips 16 shown in all of the figures and appearing more in detail in Figures 2, 4, and 5. The clips shown are preferably of sheet material such as a rigid sheet metal and comprise a web section 18 adapted to extend laterally and outwardly of the furring strip 12, as shown in Figs. 2 and 5, and terminating in turned-over, laterally-extending prongs 20. The prongs 20 extend oppositely on either side of the plane of the web 18 and are arranged on spaced axes which facilitates their manufacture from a single piece of sheet metal. It should be noted that the prongs 20 are tapered to facilitate entry into the edges of the tiles 14, into which they may be accordingly readily driven. This is clearly shown in Figure 2. One of the prongs 20 of the clip has been embedded into the edge of the tile indicated by the letter A to bring the web 18 flatwise against the said flat edge, the oppositely extending free prong 20 being then in position to embed itself in the edge or end surface of the next succeeding tile to be brought up in edge to edge abutting relationship with the tile A.

It is particularly important to note in accordance with the present invention that the web 18 is relatively wide and terminates at its opposite extremity in a laterally extending vertical flange 22 and an angularly disposed abutment portion 24. The flange 22 is, similarly to the prongs, bent out of the plane of the web 18 by a simple manufacturing step but extends in a plane normal to the plane of the prongs 20. It is the purpose of this flange to accommodate the nail or fastener which joins the clip to the furring strip 12, and to this end the flange 22 is apertured at 26. The web 22 accordingly may be nailed flatwise against the upstanding side or surface of the furring strip 12, as clearly shown in Figs. 2 and 5, preferably by a plaster board nail 28.

While it has been discovered that fastening clips nailed directly to the under-side of the furring strips normally tend to loosen or sag in service, it should be noted that in accordance with the present invention the stresses are applied transversely, or in shear, to the fastener 28. Therefore, any tendency to pull out or actually remove the fastener is negligible, remembering,

of course, that the forces which tend to remove the tiles or disarrange them with respect to the supporting structure are exerted generally transversely to the plane of the wall. It is further of extreme importance to note that in accordance with the present invention the tiles are engaged a substantial distance from the corners by the prongs 20 by virtue of the fact that the web section 18 projects and supports the prongs 20 at a substantial distance from the side of the furring strip. It has been found that this construction permits the prongs to engage the tiles without splitting or disrupting the tiles which occurs when a fastening member is driven too close to the corner. As a result of this arrangement, however, it will be obvious that a twisting or rotational stress is created by the weight of the tiles about the point of support 22. In order to resist this stress, the present invention provides the abutment or finger portion 24 forming a part of the web and terminating in an edge extending at right angles or normal to the plane of the flange 22. The upper edge of the abutment section accordingly bears against the lower flat surface of the furring strip 12 and effectively resists all twisting or turning stresses in the plane of the web 18. It will thus be seen that by cutting the end of the web 18 which is opposite the prongs 20 and along a line which is angularly acute to the upper edge of the web 18, the free flange or tab 22 is provided, which may be bent at right angles to the plane of the web 18 whereby to provide two shoulders both disposed in the plane of the web 18 at ninety degrees angularity, which shoulders are adapted to engage the corner of the furring post so that the corner rests in the apex of this cut-out portion formed when the tab 22 is bent laterally. This right angle cut-out portion forming the two shoulders in connection with the tab 22, which is nailed to the side of the furring piece, resists twisting and turning stresses in the plane of the web 18.

From the foregoing, it will be apparent that the present invention provides a tile supporting clip which may be relatively affixed to a furring strip to embrace angularly disposed surfaces of said strip in such a manner as to positively resist any twisting or rotational stresses about the axis of the strip, thereby rigidly resisting the offset forces created by the support of the tile sections and transmitting the supporting forces to the furring strip laterally of the fastener. It will be seen from the foregoing that the web being embraced between the contiguous edges of adjacent tile sections is well supported whereby the resultant tile supporting stresses are resolved in the plane of the relatively wide web section 18. It will be obvious from the foregoing, therefore, that the present clip provides a rigid supporting link substantially incapable of bending, straining, or loosening in such a direction as to vary the prearranged position of the tile upon its supporting base.

The foregoing tile clip accordingly may be employed to form a wall or ceiling construction wherein the tile slabs and clips are positively interlocked as shown in Figure 2. It will be noted that in this figure the tiles are arranged in so-called staggered relationship; that is, with the longitudinal side edges in abutment and extending continuously parallel in spaced alignment with the axis of each of the furring strips. To this end the respective furring strips are spaced on centers equivalent to the width of the tile members 14 employed. The front and rear edges

of the tiles are, however, staggered or spaced in alternate lines or columns so that they abut centrally of the side edges of the adjacent tiles. In assembling a structure such as shown in Figure 1, the tiles are assembled from left to right, as viewed in the drawings, each tile being forced upon the projecting prongs such as shown in the figure until the rear edge is contiguous to the forward edge of the rearward tile. Then two clips are driven into the position shown in Figure 2 and a fastener 28 applied to lock the clip to the adjacent corner of the furring strip.

It will be obvious from the foregoing that in accordance with the present invention there must be provided right and left clips to co-operate with either side of the furring strip. That is to say, since the attachment flange 22 should preferably be in convenient position for manipulation of the fastener 28, this flange must be arranged in such relationship as to extend forwardly of the work as assembly progresses, irrespective of which side of the furring strip the flange is arranged. In order to accomplish this function, therefore, the respective clips are relatively constructed as clearly shown in Figs. 4 and 5.

I have disclosed in Figure 3 an upstanding wall construction formed of acoustical tiles and the construction clips heretofore described. It will be understood that the embodiment shown in Figure 3 is assembled in identically the same manner as that in Figure 1 with the exception that the furring strips and tiles are arranged in a vertical plane.

I have disclosed in Figures 6 to 10 a preferred modification of the present invention which is useful in constructing wall or ceiling structures wherein the tiles are so arranged that their corners are contiguous,—that is to say, with the so-called square or matched joints. In accordance with this construction, it will be apparent in Figure 6 that both the side and end edges of the tiles 14 are arranged in contiguous alignment, the side edges being coincident with the axes of the furring strips 12 as before. While it will be understood that my foregoing clip constructions are equally as useful for supporting the tile units in the instant design nevertheless I have shown in Figs. 7, 8, and 9 a modified form of clip which coincidentally engages in supporting relationship a plurality of tiles.

The present clip comprises web sections 18 and prongs 20, the webs being extended as at 28 in what corresponds to the previously described abutment section to form an integral bridge member which joins the respective halves in a continuous unit. It may be stated in other words that the construction unit shown in Figure 10 is analogous in every respect to that previously disclosed and comprises identical or equivalent portions adapted to extend on two sides of the furring strip and perform the functions equivalent to a pair of the foregoing clips. That is to say, the present clip provides spaced flanges 22 which embrace the furring strip and are nailed to both sides thereof, as clearly shown in Fig. 7. The spacing of the flanges 22 is obviously dependent upon the length of the abutment section 28 being thereby predetermined in accordance with the width of the furring strip. In a manner similar to that shown in Figure 4, the double strip shown in Figure 10 provides two angularly disposed shoulders lying in the plane of the web portion 18 to resist torsional stresses in the plane of the web 18.

As in the previous embodiment, the present prongs are laterally spaced so as to embed within the tiles at a point spaced substantially from the corner and the offset supporting forces are rigidly resistant as before.

It is thought that the method of assembly of the ceiling or wall construction will be obvious from the foregoing descriptions. It should, in any event, suffice to point out that, with the side edges of adjacent tiles arranged as shown in Figure 7 and in alignment with the central axis of the furring strip 12, a clip is arranged with the flanges 22 oppositely embracing the furring strip driven axially until the rearward prongs are embedded in both tile members as clearly shown. Then, with the sheet web portions 18 extending vertically, fasteners 28 are driven into the furring strip 12 through the apertures 26. In progressing with the assembly subsequent pairs of tiles are arranged flatwise upon the strips 12 and in alignment, as shown in Figure 6, and forced against the forwardly extending free prongs shown in Figure 7 to bring the subsequent pair of tiles into contiguity with those shown in the figure. Further assembly involves a repetition of this process. The assembly of an upstanding wall as shown in Figure 9 is substantially identical with the procedure in the foregoing embodiment.

Figure 8 illustrates the manner in which the closed prongs 20 are embedded in the respective adjacent surfacing slabs, being supported by the upstanding web 18 from the fastening flange 22.

From the foregoing it will be apparent that the present invention provides a method and means for assembling and supporting wall or ceiling slabs or units particularly from a subjacent supporting structure which is adapted to receive nails or fasteners. The invention provides fastening clips applicable without special skill and which engage the wall units and the supporting structure permanently and positively. The present clips support the wall units freely against the furring strips in continuous edgewise alignment. In other words, the present clips do not exercise their holding or supporting function by virtue of any special tensioning or compression of the wall units in accordance with the arrangement of the clip. Thus, hitherto many fasteners have depended for their holding function upon means driven through the units or otherwise tensioning a unit into frictional engagement with the strips. In such constructions the permanency with which the parts are joined depends in large measure upon the degree to which the fastener is driven into the furring strip so that the tension or compression applied directly or indirectly to the acoustical tiles may be of considerable magnitude. In such constructions it is inevitable that the material of the slabs or tiles will be somewhat distorted by the stresses encountered. This distortion may vary objectionably by virtue of the obvious difficulty of equally tensioning each of the points of juncture. As a result, the wall surfaces appear objectionably irregular. In accordance with the present invention, however, the application of the fastener 28 at no time imposes any appreciable strain upon the outer wall surface so that the final structure is regular and uniform in appearance.

It is to be understood that, while the present invention has been specifically disclosed for illustrative purposes in connection with the construction of walls formed from so-called acousti-

cal tiles, the present clip may be employed in assembling various other types of construction elements or units including surfacing, or wall sections, or units of practically all types. Accordingly, the term "acoustical tile" as employed broadly in the specification and claims is intended to cover all such wall and construction units with which the present clip may be employed. In particular, the term "acoustical tile" is intended to cover, in its broad aspect, all wall surfacing units where sides or edges are adapted to receive engaging prongs, or to be otherwise embraced or engaged to an adjacent supporting structure.

Changes may be made in the form, construction and arrangement of the parts without departing from the spirit of the invention or sacrificing any of its attendant advantages, and the right is hereby reserved to make all such changes as fairly fall within the scope of the following claims.

The invention is hereby claimed as follows:

1. A construction clip for supporting surfacing tiles and the like comprising a web portion adapted to extend between abutting edges of adjacent surfacing units, prong means located adjacent one extremity of the web and disposed in a plane extending angularly to that of the web, and means adjacent the other extremity of the web for securing the web to a furring strip or the like and comprising an attachment flange extending in a plane disposed at an angle to the plane of the web and to the plane of said prong means for engaging the face of a furring strip, the plane of said flange being offset substantially outwardly beyond the center line of said prong means whereby the load imposed upon the prong means is adapted to set up a twisting torque about the region of the attachment flange, and abutment means extending outwardly beyond said flange at an angle thereto and operative to engage an angularly disposed face of the furring strip to resist said torque.

2. A construction clip for supporting surfacing tiles and the like comprising a web portion adapted to extend between abutting edges of adjacent surfacing units, prong means located adjacent one extremity of the web and disposed in a plane extending angularly to that of the web, and means adjacent the other extremity of the web for securing the web to a furring strip or the like and comprising an attachment flange extending in a plane disposed at an angle to the plane of the web and to the plane of said prong means for engaging the face of a furring strip, the plane of said flange being offset substantially outwardly beyond a lateral side margin of said prong means whereby the load imposed upon the prong means is adapted to set up a twisting torque about the region of the attachment flange, and abutment means extending outwardly beyond said flange at an angle thereto and operative to engage an angularly disposed face of the furring strip to resist said torque.

3. A construction clip for supporting surfacing tiles and the like comprising a web portion adapted to extend between abutting edges of adjacent surfacing units, prong means located adjacent one extremity of the web and disposed in a plane extending angularly to that of the web, and means adjacent the other extremity of the web for securing the web to a furring strip or the like and comprising an attachment flange extending in a plane disposed at an angle to the plane of the web and to the plane of said prong means for engaging the face of a furring strip,

the plane of said flange being offset substantially outwardly beyond the center line of said prong means whereby the load imposed upon the prong means is adapted to set up a twisting torque about the region of the attachment flange, and abutment means presenting an abutment margin extending outwardly beyond said flange substantially in the plane of the web at an angle to the flange and operative to engage an angularly disposed face of the furring strip to resist said torque.

4. A construction clip for supporting surfacing tile and the like comprising a web portion adapted to extend between abutting edges of adjacent surfacing units, prong means located adjacent one extremity of the web and extending laterally therefrom, and means for securing the clip to a furring strip or the like and located on the web at a position remote from said prong means, said securing means comprising an attachment flange adapted for fastening flatwise against the outer surface of a furring strip, said attachment flange being disposed in a plane extending laterally from said web, the plane of said flange being offset a substantial distance outwardly on one side of the center line of said prong means, whereby the load supported by the prong means is adapted to set up a twisting moment in the region of the fastening means, and abutment means located substantially in the plane of the web and extending outwardly beyond said attachment flange at an angle thereto and operative to engage an angularly disposed face of the furring strip to positively resist said twisting moment.

5. A construction clip for supporting surfacing tile and the like comprising a web portion adapted to extend between abutting edges of adjacent surfacing units, prong means located adjacent one extremity of the web and extending laterally therefrom, and means for securing the clip to a furring strip or the like and located on the web at a position remote from said prong means, said securing means comprising a pair of spaced, parallel attachment flanges adapted for fastening flatwise against the outer surface of a furring strip, said attachment flanges being disposed in planes extending laterally from said web, the planes of said flanges being offset a substantial distance outwardly of one side of the center line of said prong means, whereby the load supported by the prong means is adapted to set up a twisting moment in the region of the fastening means, and abutment means located substantially in the plane of the web and extending outwardly between said attachment flanges at an angle thereto and operative to engage an angularly disposed face of the furring strip to positively resist said twisting moment.

6. A construction clip for supporting surfacing tiles and the like comprising a web adapted to project between abutting edges of adjacent surfacing units, said web extending in a longitudinal axial direction defined by prong means located adjacent one extremity of said axis and extending laterally from the web and means spaced along said axis for securing the clip to a furring strip or the like, said securing means including a line of severance formed in said web along a line extending at an acute angle to the said longitudinal axis of the web, one edge of the severance providing an abutment edge adapted to impinge a face of a furring strip in abutting relation, the opposite edge portion of the severance being bent laterally to the web.

along a line extending at an angle to the abutment edge to form an attachment flange, said attachment flange being disposed in a plane extending generally parallel to the axis of said prong means and making an acute angle with said longitudinal axis of the web but being offset a substantial distance on one side of the center line of said prong means whereby a twisting torque set up by the load imposed on said prong means is adapted to be resisted by said abutment edge.

7. A construction clip for supporting surfacing tile and the like comprising a web portion adapted to extend between abutting edges of adjacent surfacing units, prong means located adjacent one extremity of the web and extending laterally therefrom, and means for securing the clip to a furring strip or the like and located on the web at a position remote from said prong means, said securing means comprising an attachment flange adapted for fastening flatwise against the outer surface of a furring strip, said attachment flange being disposed in a plane extending laterally from said web, the plane of said flange being offset a substantial distance outwardly on one side of the center line of said prong means, whereby the load supported by the prong means is adapted to set up a twisting moment in the region of the fastening means, and abutment means located substantially in the plane of the web and extending outwardly beyond said attachment flange at an angle thereto and operative to engage an angularly disposed face of the

furring strip to positively resist said twisting moment, and a second attachment flange extending laterally from said abutment edge in spaced parallel relation to said first mentioned attachment flange for embracing the opposite face of the furring strip.

8. A construction clip for supporting surfacing tiles and the like comprising a web adapted to project between abutting edges of adjacent surfacing units, said web extending in a longitudinal axial direction defined by prong means located adjacent one extremity of said axis and extending laterally from the web and means spaced along said axis for securing the clip to a furring strip or the like, said securing means including a line of severance formed in said web along a line extending at an acute angle to the said longitudinal axis of the web, one edge of the severance providing an abutment edge adapted to impinge a face of a furring strip in abutting relation, the opposite edge portion of the severance being bent laterally to the web along a line extending at an angle to the abutment edge to form an attachment flange, said attachment flange being disposed in a plane at substantially right angles to said abutment edge but being offset a substantial distance on one side of the center line of said prong means whereby a twisting torque set up by the load imposed on said prong means is adapted to be resisted by said abutment edge.

LEON F. URBAIN.
